US00D766368S

(12) United States Design Patent (10) Patent No.: US D766,368 S
(45) Date of Patent: * Sep. 13, 2016

(54) RULED FILE FOLDER

(71) Applicant: Ideastream Consumer Products, LLC,
Cleveland, OH (US)

(72) Inventors: Eric Fitzgerald Klosky, Chagrin Falls,
OH (US); Anthony J. DeCarlo, Parma,
OH (US)

(73) Assignee: IdeaStream Consumer Products,
LLC, Cleveland, OH (US)

() Term: 15 Years

(21) Appl. No.: 29/537,198

(22) Filed: Aug. 24, 2015

Related U.S. Application Data

(60) Division of application No. 29/437,884, filed on Nov.
21, 2012, now Pat. No. Des. 739,893, which is a continuation-in-part of application No. 29/427,218, filed on Jul. 16, 2012, now Pat. No. Des. 739,892.

(57) CLAIM

We claim the ornamental design for a ruled file folder, as shown and described.

DESCRIPTION

FIG. 1 is a front/right/top perspective view of the first embodiment of a ruled file folder showing our new design;
FIG. 2 is a front/left/top perspective view thereof;
FIG. 3 is a front/right/top perspective view thereof, with a corner curled down to expose the interior of the file folder;
FIG. 4 is a front elevational view thereof;
FIG. 5 is a rear elevational view thereof;
FIG. 6 is a top plan view thereof;
FIG. 7 is a bottom plan view thereof;
FIG. 8 is a right side elevational view thereof;
FIG. 9 is a left side elevational view thereof;
FIG. 10 is a front/right/top perspective view of the second embodiment of a ruled file folder showing our new design;
FIG. 11 is a front/left/top perspective view thereof;
FIG. 12 is a front/left/top perspective view thereof, with a corner curled down to expose the interior of the file folder;
FIG. 13 is a front elevational view thereof;
FIG. 14 is a rear elevational view thereof;
FIG. 15 is a top plan view thereof;
FIG. 16 is a bottom plan view thereof;
FIG. 17 is a right side elevational view thereof; and,
FIG. 18 is a left side elevational view thereof.
